CLAIM

The ornamental design for a soap dispenser, as shown and described.

DESCRIPTION

FIG. 1 is a top plan view of a soap dispenser showing my new design.

FIG. 2 is a front elevational view thereof.

FIG. 3 is a right side elevational view thereof.

FIG. 4 is a left side elevational view thereof.

FIG. 5 is a rear elevational view thereof; and,

FIG. 6 is a bottom plan view thereof, with the broken-line disclosure being understood to be a portion of the article in which the claimed design is embodied, but forms no part of the claimed design.
